COMBINATION DOOR KNOCKER AND PULL

Gerald Stahl, Rye, N. Y., assignor to The Stanley Works, New Britain, Conn., a corporation of Connecticut

Application February 3, 1953, Serial No. 23,412

Term of patent 7 years

(Cl. D10—7)

To all whom it may concern:

Be it known that I, Gerald Stahl, a citizen of the United States, residing at Rye, in the county of Westchester, State of New York, have invented a new, original, and ornamental Design for a Combination Door Knocker and Pull, of which the following is a specification, reference being had to the accompanying drawing forming a part hereof.

The figure is a perspective view of a combination door knocker and pull, showing my new design.

The rear of the horseshoe portion is plain and unornamented.

I claim:

The ornamental design for a combination door knocker and pull, substantially as shown and described.

GERALD STAHL.
